(57) **CLAIM**

We claim the ornamental design for a tactical reticle for a weapon aiming device, as shown and described.

DESCRIPTION

FIG. 1 is a view of a tactical reticle for a weapon aiming device, as viewed through an eyepiece end of a riflescope; and,

FIG. 2 is a perspective view showing of an environment of use for the tactical reticle of FIG. 1.

In FIGS. 1 and 2, the dashed lines indicate environmental features that form no part of the claimed invention. The copyright notice in FIG. 1 forms no part of the claimed invention.
